WILLIAM C. GEER, OF AKRON, OHIO, ASSIGNOR TO THE B. F. GOODRICH COMPANY, OF NEW YORK, N. Y., A CORPORATION OF NEW YORK

ELECTRODE

Application filed April 8, 1925. Serial No. 21,532.

This invention relates to electrodes of the character employed for the preparation of chemically pure metal cathodes, of the character which serve as nucleus or initial plates in the electrolytic deposition of metals, and has for an object to provide an electrode on which a nucleus plate of requisite size may be electrolytically deposited and readily removed.

10 It is the customary practice in the electrolytic purification of copper to employ a relatively thin plate of electrolytically deposited copper as an initial cathode or nucleus plate upon which the purified copper is deposited to build up an ingot of commercial size. Heretofore, the initial cathode has been formed on a large, heavy, oil-coated, copper electrode, called a "stripping plate," from which it is removed by pulling off the thin 20 deposited copper plate.

25 There are certain difficulties inherent in this mode of operation. The copper deposits around the edges of the electrode make it necessary to cut off the edges to open up a line of cleavage between the electrode and the deposited plate, giving a certain amount 30 of copper scrap which must be reworked, and, due to the cohesion of copper to copper, the stripping operation is accompanied by a considerable loss in defective plates.

35 In the present invention these difficulties are overcome to a large degree by the employment of a plate electrode made of a vulcanized-rubber composition containing a sufficient amount of a conducting material, such as graphite, and provided with a non-conducting hard-rubber border. The copper when precipitated from solution by an electric current will thus be deposited only over 40 the central or graphite-containing portion of the electrode and the newly formed copper plate of electrolytic metal may be readily stripped therefrom.

45 Of the accompanying drawings, Fig. 1 is a perspective view of an electrode embodying my invention; Fig. 2 is a section on line 2-2 of Fig. 1; and Fig. 3 is a perspective view of a modified form of electrode, parts being broken away to show the inserted copper 50 plate.

Referring to the drawings, I show in Figs. 1 and 2 an electrode consisting of a body portion 10 of an electrically-conducting vulcanized rubber having an upstanding lug 11 at one side, and a border portion 12 of non-conducting hard rubber. As shown, the border 12 does not extend across the end of the lug 11 since this portion of the electrode is in use always above the level of the electrolyte. The lug 11 is provided with a metal bushing 13 for the connection of an electric current supply wire thereto.

55 In making the electrode, a conducting rubber composition suitable for the body-portion is prepared, and then shaped to the form desired, preferably the rectangular form shown in the drawing. The border strips, cut or extruded from a suitable hard-rubber composition, are then placed about the body portion, and the whole is cured, preferably 60 in a mold of proper size, under heat and pressure to form an electrode in which the body and the border are coalesced into a truly integral structure. I have found that a composition consisting of rubber, 100 parts by 65 weight, sulfur 33 parts, graphite 150 parts, organic accelerator 1 part, conducts electricity with a fair degree of efficiency, receives deposition of copper uniformly in such manner as to form satisfactory sheets or plates, 70 and permits the ready stripping of the plates deposited thereon without injury to the copper plates or to the rubber electrode. The border composition should preferably have 75 vulcanization characteristics similar to those of the body portion, and I have found that the substitution of slate-flour for the graphite of the above recipe produces a satisfactory 80 non-conducting compound.

85 In the modification illustrated in Fig. 3, the body portion of the electrode is formed of a central copper plate 15 either side of which is covered with a layer 16 of an electrically-conducting rubber compound, the copper insert serving to secure a better distribution of 90 current throughout the exposed surfaces of the body-portion. The border 12 is constructed and the whole electrode is assembled 95 and cured in a manner similar to that above set forth.

In using either of the electrodes herein described for forming a cathode sheet or nucleus plate for use in electrolytic purification of copper, the electrode is immersed in a suitable electroplating solution, such as a strong aqueous solution of potassium cyanide and blue vitriol, and the lug 11 connected with the negative conductor of an electric circuit. A copper plate, connected with the positive conductor of an electric circuit, is also suspended in the electroplating solution. The flow of current through the solution effects a deposition of copper only on the graphite surfaces of the electrode, leaving the non-conducting border portion free of deposited copper. When a suitable thickness of copper has been deposited on the electrode, usually about $\frac{1}{16}$ inch, the electrode is taken from the solution, washed, and the sheet of copper stripped therefrom. The stripping operation is readily performed since the deposited sheet is confined to the area of the graphite body portion, to which the copper does not firmly adhere, thus giving well defined edges to the sheet at the junction of the border with the body portion of the electrode.

While I have specified herein the use of graphite in an electrically-conducting rubber composition, it is to be understood that other comminuted electrical conductors may be employed in lieu thereof. Thus, comminuted copper may be used where a copper cathode is to be formed, or zinc dust, where it is desired to form a zinc cathode. I therefore do not wholly limit my claims to the specific structures herein described.

I claim:

1. A plate electrode comprising a body portion consisting of a sheet of metal covered on both faces with an electrically-conducting rubber, and a border of non-conducting hard rubber surrounding said body portion and formed integrally therewith.

2. A plate electrode comprising a body portion consisting of a sheet of copper covered on both sides with a hard rubber compound containing a high percent of graphite, and a border of non-conducting hard rubber surrounding said body portion, the whole being united into an integral plate by vulcanization.

3. A plate electrode comprising a metal core covered at least in part with an electrically-conductive rubber composition.

4. A plate electrode comprising a sheet of metal covered on both faces with an electrically-conductive rubber composition.

5. A plate electrode including a body portion comprising a sheet of metal covered at least as to one face with an electrically-conductive rubber composition, and a border of non-conductive material united integrally thereto.

6. A plate electrode including a body portion comprising a sheet of metal covered on both sides with an electrically-conductive rub-

ber composition, and a border of non-conductive material united integrally to the body portion.

7. An electrode comprising an electrically conducting central portion and an electrically non-conducting border portion, both of said portions being of hard rubber vulcanized simultaneously in pressure contact one with the other to produce a single seamless body.

In witness whereof I have hereunto set my hand this 1st day of April, 1925.

WILLIAM C. GEER.
